EXERCISING APPARATUS

Earl H. Fundom, West Liberty, Ohio; Doris Jane Fundom, executrix of said Earl H. Fundom, deceased

Application January 21, 1954, Serial No. 405,276

6 Claims. (Cl. 272—58)

This invention relates to an exercising apparatus and more particularly to a hand and foot control mechanism for use in providing exercise to any bed or chair ridden patient.

The primary object of this invention resides in the provision of an apparatus designed for exercising the joints and muscles of a patient's body even though he may be bedridden or seated in a wheel chair so that the patient may obtain the necessary exercise for conditioning all portions of his body.

The construction of this invention features means whereby a patient may readily exercise his limbs to the extent which he is capable, the device being designed to be utilized to obtain a stroke of such length as the invalid is capable thereby enabling progressive exercising of defective muscles due to paralysis and the like. Additionally, limb supports are incorporated and used in conjunction with pedals and hand control arms to thereby enable a patient to exercise his limbs while they are being suitably supported.

Still further objects and features of this invention reside in the provision of an exercising apparatus that may be readily attached to the bed rail of a hospital bed or the like, which is strong and durable, simple in construction and manufacture, having a minimum number of moving parts thereby assuring substantially fool-proof operation, and which is inexpensive to produce thereby permitting wide distribution.

These, together with the various ancillary objects and features of the invention which will become apparent as the following description proceeds, are attained by this exercising apparatus, a preferred embodiment of which has been illustrated in the accompanying drawings, by way of example only, wherein:

Figure 1 is a perspective view of the exercising apparatus according to the present invention;

Figure 2 is a top plan view of this device;

Figure 3 is a side elevational view of the exercising apparatus with parts thereof being broken away to show all of the parts in greater detail;

Figure 4 is a vertical sectional view as taken along the plate of line 4—4 in Figure 3;

Figure 5 is a sectional detail view as taken along the plane 5—5 of Figure 3;

Figure 6 is an elevational view illustrating the manner in which the device may be readily secured to the rail of a bed; and

Figure 7 is a sectional detail view illustrating the telescoping construction of the limb support standards.

With continuing reference to the accompanying drawings wherein like reference numerals designate similar parts throughout the various views, reference numeral 10 generally designates the exercising apparatus comprising the present invention which is constructed upon a base 12 having a plurality of ears 14 depending therefrom to which there are attached suction cups 16 for use in attaching and securing the exercising apparatus

2

10 to any suitable surface. In lieu of utilizing the suction cups 16 there is provided a suitable bed rail clamp 18 which is attached to the base and which is utilized for attaching the exercising apparatus to the bed rail 20 of a bed 22 in the manner as is best shown in Figure 6. A socket 22 within which there is secured an arcuate upwardly extending handle 24 for carrying the exercising apparatus 10 is provided, the handle 24 also serving as a spacing rib or support for any cover for the exercising apparatus 10.

The base 12 is provided with a pair of elongated slots 26 and 28 therethrough. Rotatably mounted on a pair of shafts 30 within the confines of the base 12 are a pair of pulleys 32 about which an endless belt 34 is entrained. The bight portions of the belt 34 are in alignment with the slots 26 and 28 and clamp members 36 are secured to the belt 34. The clamps 36 include plates 38 which extend upwardly through the slots 26 and 28 and which carry slides 40 which are adapted to slidably engage the top of the base 12. A pair of pedals 42 and 44 are adjustably mounted on the plates 38 by means of bolts 46, wing nuts 48 which pass through the mounting plates 50 and 52 pinned at 54 and 56 or otherwise attached to the pedals 42 and 44.

The pedal 42 carries a spaced pair of ears 58 to which a lower section 60 of a hand control arm is attached. Likewise the pedal 44 carries ears 62 to which a hand control arm section 64 is pivotally mounted. Cylindrical telescoping sections 66 and 68 are adjustably secured on the control arm sections 60 and 64 by means of fasteners 70 and 72 respectively.

In the embodiment of the invention as shown only in Figures 1 and 7 there are provided a pair of outwardly extending mounting members 74 and 76 adjacent the rear of the base 12 and secured thereto. The mounting members provide bearing supports for standard sections 78 and 80 which have telescoping standard sections 82 and 84 adjustably attached thereto by means of fasteners 86, the standard sections 82 and 84 being slidable over the sections 78 and 80. Adjustably attached to the standards 82 and 84 as by fasteners 88 are straps 90 and 92 which are adapted to be arranged in encompassing relationship about a limb of a patient using this exercising apparatus.

The operation of this exercising apparatus actually is quite simple. The pedals have a stroke ranging up to approximately the full length of the slots 26 and 28. It is not necessary that the pedals 42 and 44 complete a stroke of any given length before the return stroke can be initiated. This enables patients in varying degrees of incompatibilities to obtain satisfactory exercise from this device. By the patient or invalid applying pressure first with one foot and then another the operation of the device can be achieved. The straps 90 and 92 mounted on the pivoted standards suitably support the joints of the patient. Further, motion of the legs can be induced using the arm control members by grasping the handle portions of the telescoping sections 66 and 68. Thus, utilizing both the hand control mechanisms and the foot mechanisms a patient can exercise the ankles, knees, hips, hands, arms, shoulders, and joints and muscles utilizing the single device. Since it may be readily attached to a bed rail or to a supporting surface such as a floor, the device is able to be utilized by either a bedridden patient or by one in a wheel chair.

Since from the foregoing the construction and advantages of this exercising apparatus are readily apparent, further description is believed to be unnecessary.

However, since numerous modifications will readily occur to those skilled in the art after a consideration of the foregoing specification and accompanying drawings,

it is not intended to limit the invention to the precise embodiment shown and described, but all suitable modifications may be readily resorted to.

What is claimed as new is as follows:

1. An exercising apparatus comprising a base having a pair of spaced slots therein, a pair of pulleys rotatably mounted below said base, an endless belt entrained about said pulleys with bight portions of said belt positioned below said slots and in alignment therewith, clamp members engaging said bight portions and extending upwardly through said slots, and pedals adjustably pivotally mounted on said clamp members.

2. An exercising apparatus comprising a base having a pair of spaced slots therein, a pair of pulleys rotatably mounted below said base, and endless belt entrained about said pulleys with bight portions of said belt positioned below said slots and in alignment therewith, clamp members engaging said bight portions and extending upwardly through said slots, and pedals adjustably pivotally mounted on said clamp members, said pedals having control arms pivotally attached thereto, said control arms including telescoping sections adjustably secured to each other.

3. An exercising apparatus comprising a base having a pair of spaced slots therein, a pair of pulleys rotatably mounted below said base, an endless belt entrained about said pulleys with bight portions of said belt positioned below said slots and in alignment therewith, clamp members engaging said bight portions and extending upwardly through said slots, and pedals adjustably pivotally mounted on said clamp members, limb support standards pivotally secured to said base, and limb straps carried by said standards for supporting limbs of a patient.

4. An exercising apparatus comprising a base having a pair of spaced slots therein, a pair of pulleys rotatably mounted below said base, an endless belt entrained about said pulleys with bight portions of said belt positioned below said slots and in alignment therewith, clamp members engaging said bight portions and extending upwardly through said slots, and pedals adjustably pivotally

4
mounted on said clamp members, limb support standards pivotally secured to said base, and limb straps carried by said standards for supporting limbs of a patient, said pedals having control arms pivotally attached thereto.

5. An exercising apparatus comprising a base having a pair of spaced slots therein, a pair of pulleys rotatably mounted below said base, an endless belt entrained about said pulleys with bight portions of said belt positioned below said slots and in alignment therewith, clamp members engaging said bight portions and extending upwardly through said slots, and pedals adjustably pivotally mounted on said clamp members, limb support standards pivotally secured to said base, and limb straps carried by said standards for supporting limbs of a patient, said pedals having control arms pivotally attached thereto, said control arms including telescoping sections adjustably secured to each other.

20 6. An exercising apparatus comprising a base having a pair of spaced slots therein, a pair of pulleys rotatably mounted below said base, an endless belt entrained about said pulleys with bight portions of said belt positioned below said slots and in alignment therewith, clamp members engaging said bight portions and extending upwardly through said slots, and pedals adjustably pivotally mounted on said clamp members, limb support standards pivotally secured to said base, and limb straps carried by said standards for supporting limbs of a patient, said pedals having control arms pivotally attached thereto, said control arms including telescoping sections adjustably secured to each other, said base having a bed rail 25 30 engaging clamp attached thereto.
